FLUID-PRESSURE-OPERATED VISE USING
HYDRAULIC LOCK AND SCREW-ACTUATED RAM FOR CLAMPING AND HAVING A
FLUID BY-PASS FOR QUICK SEPARATION
OF JAWS

Kurtiss P. Schenke, New York, N. Y.

Application July 13, 1946, Serial No. 683,345

9 Claims. (Cl. 81—17.2)

1

The present invention relates to improvements in vises and work holding devices and more particularly to an improved fluid or hydraulic vise of a quick-acting type.

It is a major object of this invention to provide an improved vise or other work holder which utilizes hydraulic or other fluid power to greatly increase the magnitude of the manual forces which are applied. A further object resides in the provision of a manual actuating screw of relatively short movement cooperatively associated with a hydraulic ram and a hydraulic lock by means of which the vise can selectively be tightened or released and when released is free to be pulled open without the necessity of further rotation of the screw.

A further object lies in such an arrangement in a hydraulic vise wherein a relatively few turns of the manual screw converts the vise from its freely movable condition through which it can easily be adjusted for varied sizes of work to the condition in which it grips the work with a high hydraulic or mechanical advantage. A still further object lies in an arrangement in which the transition from mechanical movement of the screw to hydraulic movement for gripping the work is entirely automatic and relieves the operator of the necessity of performing an additional step as required in most prior devices. It is a further object to provide a screw actuated hydraulic vise in which the screw is utilized to selectively condition the vise and to actuate the hydraulic means but wherein the screw is automatically relieved of the high stresses reacting through the vise structure when the work is gripped by the hydraulic pressure.

It is accordingly a corollary object to provide such a vise of high gripping power in which the screw mechanism is subjected to relatively light forces and consequently very little wear. A further object resides in providing a vise capable of such high pressures and capacity that it is usable as a hydraulic press for stamping, punching and other operations. Other objects of the invention include the provision of an improved vise which is time-saving and quick-acting in use and which incorporates a novel arrangement of its simple and trouble-free parts. Other objects and advantages will become apparent to those skilled in the art after reading the present description and the accompanying drawings forming a part hereof, in which:

Fig. 1 is a side elevational view of a vise embodying the present invention;

Fig. 2 is a sectional view to a larger scale of the screw and hydraulic mechanism of the vise of Fig. 1 in its work-gripping condition; and

Fig. 3 is a similar view of the same mechanism in its disengaged condition.

Referring now to Fig. 1 the numeral 5 design-

2

nates the stationary portion of a vise having a fixed stock or jaw 6. The movable portion is designated by the numeral 7 and has a corresponding movable stock or jaw 8. A tongue or bar member 9 is rigidly attached to the movable portion 7 and extends through a suitable aperture within the fixed portion 5 in a manner well known in the art. A flanged base portion 10 is formed at the bottom of the fixed portion and by which it may be attached to a bench 11 as by the bolts 12. It will be understood that the novel features of my invention which are about to be described are equally applicable to vises of all types whether swivelling or universal, of the drill press type, or for work clamps, holders, or jigs and fixtures.

A tubular member 13 is preferably threadedly attached to the movable portion 7 as at 34 at its outer end and is similarly threaded at its inner end at 35 to a large piston 14 reciprocable within a chamber or cylinder 15 formed within the fixed portion 5, dividing the cylinder into the portions 15a and 15b. The piston is provided with a suitable seal or packing at 14p at its periphery to prevent leakage of fluid from one end of the cylinder to the other and a suitable seal is also provided at 5p to prevent fluid leakage through the end of the cylinder around the tube 13. The far end of the cylinder is closed by a cylinder head 16 suitably attached by a plurality of studs or screws 17. The end plate or cylinder head 16 is suitably apertured and threaded to receive a filler pipe and cap assembly at 18 to provide both a reserve chamber for fluid and a column of air above the fluid for purposes to be hereinafter explained. A screw rod 19 threadedly engages the aperture 7a in the movable portion 7 and is coaxially disposed with respect to the bore in the tubular member 13. Fixed to the end of the screw rod 19 is a ball hub 20 from which a handle 21 is supported for manually rotating the screw. The work is indicated by the construction lines 22 and the vise is adjustable to receive a wider work piece such as 22a at which time the hub of the handle will be approximately at the position 28a.

Referring now to Fig. 2 it will be noted that the screw rod 19 continues co-axially within the tube 13 as a straight piston rod 23 on which a small piston or ram 24 is fixedly mounted by the threaded lock nut 25 tightened against the shoulder 26. The ram piston 24 is reciprocable within the tube 13 for a limited distance and hydraulic fluid is prevented from passing the periphery of the ram by the seal 24p. The piston rod has an extended reduced diameter portion 27 on which is slidably mounted a piston valve 28 having a peripheral channel and a plurality of communicating radial passages 38. An enlarged ported end or detent 29 is attached to the inner end of the piston rod 27 and is capable of extending through the central opening in the piston 14 and

through the end of the tube 13. The piston valve 28 is spring-pressed by the compression spring 30 restrained by the detent 31 which is fixed to the rod 27. The travel of the piston valve 28 is limited axially by the annular ring detents 32 and 33 fixed to the inner wall of the tube 13 which wall is provided with apertures or ports 36 and 37. The piston 14 divides the cylinder 15 into a reservoir portion 15a and a working portion 15b and all hydraulic forces acting upon the piston 14 are transmitted directly to the movable vise portion 7 to which it is directly attached by the small bore cylinder tube 13.

In preparing the vise for use it will be filled with a suitable oil or other hydraulic fluid such that both chambers 15a and 15b are filled with fluid up to the level indicated on the filler pipe 18 in Fig. 1. The connection 5a may be utilized to bleed off trapped air in the filling operation and both cylinders should be filled with fluid and free from air. The connection 5a may also be used for an indicating pressure gage and will show the clamping pressures being developed between the vise jaws 6 and 8. The screw threads 19 are righthanded and the handle 21 is rotated clockwise looking toward the working end of the vise with the jaws in light contact against the work 22.

In the position of the elements shown in Fig. 2 it will be seen that the screw 19 has been rotated clockwise to a point where the piston end 29 has been extended beyond the piston valve 28 which, under the influence of the spring 30 has been urged against the detent 33. In this position of the piston valve 28 and the piston end 29 the ports 38 in the piston valve are cut off from the passages in 29 and the port 36. There is accordingly no fluid communication from one side of the piston 14 to the other, or between chambers 15a and 15b and a hydraulic lock may be said to have been created. Continued clockwise rotation of the screw 19 will assist the spring 30 in holding the piston valve closed and will build up fluid pressure within the tube 13 ahead of the ram piston 24 which pressure passes through the always open port 37 into the working chamber 15b against the face of the piston 14. A power increase or boost is accordingly obtained which is approximately in proportion to the exposed areas of the pistons 14 and 24. The greatly increased force, and reduced axial motion, applied to the piston 14 is transmitted in the form of a tensile force through the cylinder tube 13 which in turn pulls the movable jaw 8 against the work 22. The clamping force applied to the work will accordingly be of great magnitude, many times greater than the manual force applied in turning the handle 21, and the screw 19 will accordingly be relieved from transmitting the high clamping force, which is transmitted by the tube 13. Due to the relative incompressibility of the fluid in the cylinder 15 the piston 14 will be moved a relatively short distance and as a result of this short movement the residual fluid in the chamber portion 15a will be compressed against the air above the fluid level in the filling pipe 18, which air serves as a pneumatic cushion and permits the filling pipe to serve as an expansion chamber.

In order to release the clamping pressure and free the movable portion 7 to accommodate a larger work piece 22a, the screw 19 is backed off several turns to the position shown in Fig. 3. In this position it will be noted that the ram 24 has receded, permitting the pressure within the cylinder tube 13 and the chamber 15b to drop and permit the rod end 29, assisted by the pres-

sure within the chamber 15a to return the piston valve 28 to its open position against the detent 32. In this position it will be seen that the chambers 15a and 15b are in open communication through the ports 36, 38 and 29 and the hydraulic lock may be said to be broken or opened. It is accordingly not necessary to rotate the screw further inasmuch as a light outward pull on the handle 21 will permit the piston 14 and the attached movable portion 7 to be moved to the desired position, displacing fluid from chamber 15b to chamber 15a. The larger work piece can be clamped in the extended position by again rotating the screw 19 in a clockwise direction as previously described. Obviously almost any degree of hydraulic force magnification can be obtained by designing the desired ratio of exposed areas of pistons 14 and 24.

Other forms and modifications of the present invention both in respect of the general arrangement and the details of the respective elements will occur to those skilled in the art after reading the present description and drawings, but all such forms and modifications are intended to come within the scope of this invention as more particularly set forth in the appended claims.

I claim:

1. In a quick-acting vise, a movable stock, a fixed supporting stock, a rotatable screw shaft 30 threadedly engaging one of said stocks, a cylinder formed within the other said stock and filled with an incompressible fluid, a piston reciprocable within said cylinder, a tubular member connecting one of said stocks and the piston within the other said stock, a ram piston carried by said screw shaft and reciprocable within said tubular member, and a valve selectively operable by rotation of said screw shaft for by-passing the fluid in said cylinder from one side to the other side of said piston to permit quick-acting manual movement without the necessity of rotating said screw and for locking the fluid in the tubular member and in that portion of the cylinder which surrounds the tubular member, whereby actuation of said ram piston can bring said stocks together under fluid pressure.

2. In a quick-acting vise, a movable stock, a fixed supporting stock, a rotatable screw shaft threadedly engaging said movable stock, a closed cylinder carried by said fixed stock and filled with an incompressible fluid, a double-faced piston reciprocable within said cylinder, a tubular member connecting said movable stock with said piston, a ram piston carried by said screw shaft and reciprocable within said tubular member, and a valve selectively operable upon rotation of said screw shaft for by-passing the fluid in said cylinder from one side to the other side of said piston in one position of said screw shaft to permit quick-acting movement without further rotation of said screw and for locking the fluid in the tubular member and in that portion of the cylinder which surrounds the tubular member, whereby actuation of said ram piston can bring said stocks together under fluid pressure.

3. A fluid-actuated quick-acting vise including a movable stock, a fixed stock, a rotatable screw shaft threadedly engaging said movable stock, a cylinder carried by said fixed stock and filled with an incompressible fluid, a piston reciprocable within said cylinder dividing said cylinder into a fluid reservoir chamber and a fluid pressure chamber, a tubular member connecting said movable stock with said piston, normally aligned ports connecting said chambers formed

within said cylinder for by-passing the fluid in said cylinder from one side to the other side of said piston for quick-acting movement of said movable stock without rotation of said screw, and valve and fluid-pressure-generating means sequentially actuated by rotation of said screw for closing said by-pass ports and drawing said stocks together by increasing the fluid pressure within said fluid pressure chamber.

4. A fluid-actuated vise including an internally threaded movable stock, a fixed stock having a cylinder carried thereby, said cylinder being filled with an incompressible fluid, a rotatable screw shaft threadedly engaging said movable stock, a piston having opposite faces being reciprocable within said cylinder, a tubular member of smaller diameter than said piston connecting said movable stock with said piston, normally aligned ports through the wall of said tubular member and through said piston providing fluid communication with both faces thereof, valve means actuated by said screw shaft for closing said ports and making said piston fluidly effective, and fluid-pressure-generating means actuated by further rotation of said screw shaft in the same direction for the fluid actuation of said piston in causing clamping engagement of said vise stocks.

5. A fluid-actuated vise including an internally threaded movable stock, a fixed stock having a cylinder carried thereby, said cylinder being filled with an incompressible fluid, a rotatable screw shaft threadedly engaging said movable stock, a piston reciprocable within said cylinder and dividing said cylinder into two chambers, a tubular member of smaller diameter than said piston co-axially disposed about said screw shaft and connecting said movable stock with said piston, normally aligned ports through the wall of said tubular member and through said piston providing fluid communication with the chambers formed on both sides of said piston, a ported valve slidably carried by said screw shaft and actuated by said screw shaft for closing said ports and making said piston fluidly effective, and fluid-pressure-generating means actuated by said screw shaft to increase effective fluid pressure upon said piston so as to cause clamping engagement of said vise stocks.

6. A fluid-actuated vise including an internally threaded movable stock, a fixed stock having a cylinder carried thereby, said cylinder being filled with an incompressible fluid, a rotatable screw shaft threadedly engaging said movable stock, a piston reciprocable within said cylinder, a tubular member connecting said movable stock with said piston, normally open by-pass means providing fluid communication between the chambers formed within said cylinder on each side of said piston, ported valve means actuated by said screw shaft for closing said by-pass and hydraulically locking said piston, fluid-pressure-generating means actuated by said screw shaft and effective within one of said fluid chambers of said cylinder to actuate said piston and to force said movable stock toward said fixed stock and lost-motion means providing for continued actuation of said fluid-pressure-generating means by said screw shaft while maintaining said valve means in its closed position.

7. A fluid-actuated quick-acting vise including a movable stock, a fixed stock, a rotatable

screw shaft threadedly engaging one of said stocks, a closed cylinder carried by the other of said stocks and filled with an incompressible fluid, a piston within said cylinder dividing said cylinder into two chambers, a tubular member of lesser diameter than said piston connecting one of said stocks and said piston, a fluid actuating ram positioned within said tubular member and connected to said screw shaft for reciprocation within said tubular member upon rotation of said screw shaft, a by-pass fluidly communicating with both said chambers for quick-acting operation of said movable stock independent of said screw shaft, said screw shaft being sequentially operable to close said by-pass to lock the fluid in one of said chambers and to actuate said ram against said locked fluid thereby moving said piston and forcing said movable stock toward said fixed stock.

8. A fluid-actuated vise including a movable stock, a fixed stock, a rotatable screw shaft threadedly engaging one of said stocks, a cylinder carried by the other said stock and filled with an incompressible fluid, a piston reciprocable within said cylinder dividing the same into a force-multiplying chamber and a reservoir chamber, a tubular member connecting one of said stocks and said piston, ports through the wall of said tubular member fluidly connecting said force-multiplying chamber with the interior of said tubular member and with said reservoir chamber, a ported valve slidable on said screw shaft normally aligned with a first of said wall ports for the fluid by-passing of said piston, a second of said wall ports providing at all times fluid communication between said force-multiplying chamber and the interior of said tubular member, a ram piston carried by said screw shaft operable to create pressure against said closed ported valve within said tubular member and within said force-multiplying chamber through said second wall port for the fluid pressure actuation of said movable vise stock.

9. A fluid-actuated vise of the type set forth in claim 8 characterized by the inclusion of resilient means to maintain said ported valve in its open position wherein said piston is by-passed, and lost-motion means cooperable with said resilient means to maintain said ported valve in its closed position during further advance of said screw shaft and said ram piston during its fluid-pressure actuation of said movable vise stock.
